UNITED STATES PATENT OFFICE

GUY S. FABER, OF CHICAGO, ILLINOIS, ASSIGNOR TO JAS. P. MARSH & COMPANY, OF CHICAGO, ILLINOIS, A CORPORATION OF ILLINOIS

AUTOMATIC WATER LEVEL REGULATOR AND SAFETY SWITCH

Application filed December 6, 1928. Serial No. 324,252.

My invention relates to safety devices that will control an electrical circuit upon variation in conditions between desired limits, and more particularly it relates to mechanism operable by a float which rises and falls with the liquid level in a tank whereby an electrical circuit is completed or broken in accordance with predetermined levels of the liquid. The tank may be connected with a source of supply by a flow or gravity pipe controlled by a valve in which event breaking the circuit will actuate the mechanism to close the valve and completing the circuit will actuate such mechanism to open the valve. The supply of liquid in the tank may be replenished otherwise, as for example, by a motor actuated pump which operates when the circuit is completed and is inoperative when the circuit is broken. Because of the intermittent and irregular movement of a liquid actuated float which is governed by the elevation of the liquid in a tank, float-controlled mechanism as heretofore constructed has been unsatisfactory as an actuator of a circuit breaker. Proper operation of such switches requires that they be moved impulsively from open to closed position and vice versa, and also requires that such movement be complete and one of the objects of the invention is to provide improved means connecting such a float with a circuit breaker switch whereby the switch is actuated impulsively and completely to break or to connect a circuit.

Because of its weight, it is desirable to have the float mechanism suspended or supported other than from the switch mechanism except when the float is traveling upwardly, and another object of this invention is the provision of improved means intermittently operable to release the switch from the weight of the float mechanism.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

Fig. 1 is an elevational view of a device embodying my invention mounted upon and suspended from the top wall of a tank;

Fig. 2 is a sectional view taken on the line 2—2 of Fig. 1 and drawn to a larger scale;

Fig. 3 is a sectional view on the line 3—3 of Fig. 1 drawn to the same scale as is Fig. 2;

Fig. 4 is a view on the line 4—4 of Fig. 2; and

Fig. 5 is a section on the line 5—5 of Fig. 1. Referring now to the drawings wherein like reference characters indicate like or corresponding parts:

Any type of circuit breaker may be employed, that shown consisting of a mercury contact tube or switch 17 made of glass or other suitable material provided with contacts 15. When the tube or switch 17 is in horizontal position, the mercury bridges over or electrically connects the contacts 15, while when the tube is in tilted position the circuit is broken between the contacts 15.

Conductors 8 and 9 are connected with the contacts 15 so that the circuit through the conductors is controlled by tilting or rocking the tube 17 as will be more fully explained in the operation of the device.

In the embodiment illustrated the tilting of the tubes 17 is controlled by a float 12 which is positioned in a tank and rises and falls in accordance with the water level therein. The numerals 10 and 11 respectively designate the upper and the lower walls of the tank in which the float 12 is positioned. An upper stop member 13 and a lower stop member 14 respectively limit the upward and the downward travel of the float 12 with the level of the water in the tank.

The float 12 is operatively connected by a rod 18 with the mechanism which actuates the tube or switch 17 impulsively. Both the mechanism actuating the switch 17 and also the switch are housed or enclosed in a casing 16. A mounting member 19 supports the casing 16, the casing being fastened to the members by a plurality of screw bolts 23. The member 19 is provided with apertures 24

through which screw bolts 25 or the like are inserted for fastening the mounting member on the upper wall 10 of the tank.

A pipe 20 has a threaded connection at its upper end with the member 19 and a similarly threaded connection at its lower end with a coupling member 26. An extension pipe 21 connects the member 26 with a lower coupling member 27. The switch rod 18 is operatively connected at its upper end with the tube or switch 17 and is longitudinally movable through a bore formed in a coupling connection 28 with an extension rod 29. The rod 29 extends downwardly through the pipes 20 and 21, passing through bores formed for that purpose in the members 26 and 27. The switch rod 18 and the extension rod 29 are longitudinally movable as a unit relative to the member 19 and the pipes 20 and 21 through which the rods extend.

The pipes 20 and 21 provide a guide or runway for the float 12. The float 12 is provided for this purpose with an open centrally positioned cylindrical member 22 which forms a sleeve telescoping the pipes 20 and 21. The amount of vertical movement of the float 12 along the pipes 20 and 21 as a runway, is limited by the stop members 13 and 14. The upper and lower portions of the members 26 and 27 are preferably solid except for the bores which contain the rods 29 and their middle portions are generally cylindrical in shape with their outer walls provided with oppositely positioned vertically extending slots 30.

A transversely extending pin 31 is positioned in the coupling member 26 with the ends of the pin projecting through the slot 30. The pin 31 is mounted upon the extension rod 29 and is provided with an annular shaped midportion 33 through which the rod 29 extends. A cotter pin 32 extends longitudinally through the pin 31 and transversely through the rod 29 thereby fastening the pin 31 on the rod 29. The bottom coupling member 27 is constructed similarly to the coupling member 26 and has a pin 31 similarly fastened to the rod 29. The pins 31, the coupling members 26 and 27, and the cotter pins 32 together form the upper and lower stop members 13 and 14. It is obvious that both of the pins 31 will move with the rod 29 upon which they are mounted, and it is also obvious that the longitudinal movement of the rod 18 and the rod 29 in the pipes 20 and 21 is limited by the permissible movement of the pins 31 in their slots 30.

Vertical actuation of the connected rods 18 and 29 is accomplished by the cooperation of the float sleeve 22 with the pins 31. The upper end of the float sleeve 22 comes into contact with the uppermost of the pins 31 as the water level approaches its predetermined upper limit, thereby carrying upwardly with it the connected rods 18 and 29. The sleeve

22 likewise contacts with the lower pins 31 as the level of the water in the tank approaches the lowermost predetermined limit and carries downwardly with it the rods 18 and 29 as the water level recedes.

Mechanism is provided for instantaneously moving the switch 17 from its operative to its inoperative position and vice versa, being actuated in such movement by the longitudinal movement of the switch rod 18. For this purpose a disk 34 is fixedly mounted on a shaft 35, the disk 34 being connected with the upper end of the switch rod 18 by means of a link 36. The link 36 is pivotally connected at one end to the disk 34 and at its other end the link has a pivotal connection with the rod 18. As the rod 18 is forced upwardly by the pressure of the float sleeve 22 against the uppermost of the pins 31, the link 36 is caused to rotate the disk 34 and the shaft 35. Rotation of the disk 34 and the shaft 35 moves the mercury contact switch 17 to an inoperative sloping position whereby the circuit is broken and the flow of water into the tank ceases.

The switch or tube 17 is mounted in a plate member 47 which projects through apertures (not shown) formed in a plate 48, the apertures being so formed as to permit limited rotation of the member 47. The member 47 is suitably fastened on one face of a disk 49 which is rotatably mounted on the shaft 35. A sleeve 50 is mounted on the other face of the disk 49, the amount of rotation of the disk and the sleeve being limited by the permissible movement of the member 47. Each half of the free end of the sleeve 50 is cupped out to form camming surfaces terminating in oppositely positioned tooth like projections 51. A pair of rollers 52 are suitably mounted on opposite sides of the shaft 35 and are yieldingly held against the camming surfaces of the sleeve 50 by means of a spring 53. Rotation of the shaft 35 causes the rollers 52 to ride over the camming surfaces on the end of the sleeve 50, the spring 53 at the same time yielding slowly to permit the rollers to ride over the points of the projections 51. The pressure of the spring 53 on the rollers 52 forces the sleeve 50 and the tube 17 which is mounted thereon to rotate in a direction opposite to the rotation of the shaft 35 in accordance with the limitation of rotation imposed by the apertures in the plate 48. The engagement of the rollers 52 with the relatively steep edges of the camming surfaces adjacent the projections 51 permits a rapid movement of the rollers which produces the desired impulse or quick throw of the switch upon the instant that the rollers reach the tip of the projection 51. A more detailed description of the mechanism is omitted since such mechanism is shown and claimed in my co-pending application Serial No. 322,906, filed November 30, 1928.

The switch 17 remains in inoperative position until the water level has receded to the level where the float sleeve 22 contacts with and is partially supported by the rod 31 of the stop member 14. Continued recession of the water and of the float 12 carries the rod 29 and the switch rod 18 downwardly, causing the rod 18 to operate the disk 34 and its connecting link 36. The rotation of the disk 34 causes the shaft 35 to move the tube or switch 17 back to horizontal position, as above described in which position the circuit is closed and replenishment of the water supply in the tank is started. The tube 17 remains in this horizontal operative position until the float 12 is carried by the rising water to a point where the rod 18 again moves the tube to its sloping inoperative position and thereby completes a cycle of operation.

The rods 18 and 29 are connected to the link 36 and their weight exerts a pull on the link which tends to hold the mechanism in the horizontal position of the tube 17. The tube 17 occupies its horizontal position during the upward movement of the float and during such upward travel the suspension of the rods from the link 36 is not objectionable. When the float 12 has completed its upward movement and by pushing against the upper stop member 13 has tilted the tube 17 to its inoperative position the float then travels downwardly with the recession of the liquid in the tank. The weight of the rods 18 and 29 tend to rotate the tube 17 back to horizontal and although the weight of the rods 18 and 29 is not sufficient to overcome the thrust of the spring 52 on the sleeve 50 and thereby accomplish rotation of the tube, still it is considered desirable to eliminate such a tendency and for this purpose I have provided means whereby the rods are suspended from the member 19 while the water is receding.

When the rod 18 is in its uppermost position a generally spherical shaped member 40, which is positioned in an aperture 41 formed in the member 19, is forced by a spring 42 into a groove 43 formed on the rod 18. The spring 42 yieldingly holds the spherical member 40 in its position in the groove 43. The member 40 thereby supports the rods 18 and 29 when the float 12 is out of engagement with the upper pin 31 and until the float in receding comes to rest on the lower pin 31. Any tendency which the combined weight of the rods 18 and 29 would otherwise have to actuate the mechanism controlling the position of the tube or switch 17, is avoided by thus supporting the rod from the member 19. The float 12 when descending comes in contact with the lower pin 31 and the combined weight of the float and the rods 19 and 29 is sufficient to overcome the resilience of the spring 42 and forces the spherical member 40 back into the aperture 41, thereby releasing the rod 18 from engagement with the

member 40. A bolt 44 and a lock nut 45 provide means for adjusting the spring 42 whereby the weight which will operate to release the member 40 from holding engagement with the rod 18 may be varied in any amount as desired.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described, a switch adapted to control the flow of liquid into a tank, a float in the tank, a supporting member for the switch, a vertically extending rod operatively connected with said supporting member, an upper stop member suitably mounted at a predetermined position on the rod whereby the rising float lifts the rod to open the switch, a lower stop member suitably mounted at a predetermined position on the rod whereby the weight of the receding float moves the rod downwardly to close the switch, means mounted in said supporting member operable to engage and fixedly support said rod, and spring means yieldingly holding said means in operative engagement with said rod in its elevated position until the weight of said receding float operates on said lower stop member to lower the rod by overcoming the resistance of said spring means.
2. In a device of the kind described, a switch adapted to control the flow of liquid into a tank, a float in the tank, a supporting member for the switch, a vertically extending rod operatively connected with said switch, said rod being longitudinally movable in a bore in said supporting member, an upper stop member suitably mounted at a predetermined position on the rod whereby the rising float lifts the rod to open the switch, a lower stop member suitably mounted at a predetermined position on the rod whereby the weight of the receding float moves the rod downwardly to close the switch, a horizontal plunger mounted in the supporting member, spring means yieldingly holding the end of the plunger in engagement with the rod, said rod having a recess into which the plunger enters when the rod is in its elevated position, whereby the rod is suspended from the plunger, said spring means yielding to release the plunger from support of the rod when said float rests on said lower stop member.
3. A contact switch, mechanism operable to actuate said switch impulsively, a water tank, a float movable with the water level in the tank, means operatively connecting the float with said mechanism, said means com-

- prising a vertically movable rod operatively connected at its upper end with said mechanism, upper and lower stop members suitably mounted on said rod in the path of said float to limit the rise and fall respectively of said float whereby the float, when near its uppermost level actuates the rod upwardly to a point where said switch is impulsively opened and whereby the float when near its lower level actuates the rod downwardly to impulsively close said switch, and means operable to engage and fixedly support said rod at the point corresponding to the closing of the switch, and spring means yieldingly holding said means in operative engagement with said rod from the time the switch is opened by said upward movement of the float until the switch is closed by said downward movement of the float.
- 20 4. In a device of the kind described, an impulse switch adapted to control the flow of liquid into a tank, a float in the tank, a rod movable to open and close the switch impulsively, means connecting the float with the rod, whereby the movement of the rod is controlled by the rise and fall of the float, mechanism operable to fixedly support the rod in elevated position and spring means yieldingly holding said means in operative engagement with the rod when the liquid level in said tank is above a predetermined elevation.
- 5 In a device of the kind described, an impulse switch adapted to control the flow of liquid into a tank, a vertically extending longitudinally movable rod mounted in the tank, switch actuating mechanism operatively connecting the rod with said switch, a float telescopically connected with the rod, an upper stop member suitably mounted at a predetermined point on the rod whereby the rising float lifts the rod to close the switch, a lower stop member suitably mounted at a predetermined point on the rod whereby the weight of the receding float moves the rod downwardly and opens the switch, means adapted to fixedly support the rod in its elevated position corresponding to the closed position of the switch, and spring means operable by the weight of said float to release said rod supporting means from operative engagement with the rod when said float rests upon said lower stop member.

In testimony whereof, I have hereunto signed my name.

GUY S. FABER.
